CARBURETOR

Auguste Chanard, Rueil, France

Application April 14, 1933, Serial No. 666,317
In France April 23, 1932

5 Claims. (Cl. 261—41)

This invention relates to a carburetor characterized by several rows of parallel conduits, such as small choke tubes, constituting as many unitary carburetors, the whole forming a bundle in which each row is fed by a single calibrated orifice. A suitable device, preferably constituted by a thin screen, allows to uncover and to put in action a variable number of rows.

In order that the invention may be clearly understood, it is illustrated in the accompanying drawings, given by way of example only, and in which:

Fig. 1 is an elevation.

Fig. 2 is a horizontal section made according to line 2—2 of Fig. 1.

Fig. 3 is a vertical section made according to line 3—3 of Fig. 2.

Fig. 4 is another vertical section made according to line 4—4 of Fig. 2.

Fig. 5 is a horizontal section made according to line 5—5 of Fig. 4.

Figs. 6 to 11 illustrate a constructional modification.

Fig. 6 is a vertical section.

Fig. 7 is a horizontal section made according to line 7—7 of Fig. 6.

Fig. 8 is a vertical section made according to line 8—8 of Fig. 7.

Fig. 9 is a vertical section made according to line 9—9 of Fig. 6.

Figs. 10 and 11 are detail views on an enlarged scale.

As illustrated in the drawings, Figs. 1 to 5, the new carburetor comprises a block *a*, in which are perforated, or provided upon casting, parallel conduits *b*, the profile of which is that of choke tubes, as shown in Fig. 3. These conduits are distributed, in this example, in four parallel rows *b*¹—*b*⁴, and a conduit *c* serves for running at slow speed. The said conduit *c* is provided with a diaphragm *d*, perforated with small holes, Fig. 3, so as to very exactly measure the carbureted air, in order to ensure proper operation at slow speed.

The choke conduits *b* can be opened or closed by a flexible screen *e*, slidably between the face of the block *a*, where the said choke conduits lead, and a grid *f*, provided with holes *g* corresponding to the choke conduits and rigid with a conical tub *h* connected to the engine. Between the block and the grid is arranged a packing *i*, the thickness of which is a few hundredths of a millimeter greater than the thickness of the screen, thus allowing the latter to slide without resistance, although there is no appreciable play or clearance.

The screen is actuated by toothed wheels *j*, the teeth of which enter perforations in the screen. Both wheels *j* are rigidly secured on a shaft *j*¹, on which is secured a control lever. The screen,

when it uncovers the openings, is received in a space *k*, Fig. 3, without forming any external protuberance.

Gasoline is admitted at 1, Fig. 2, and fills up a chamber *m*, the volume of which is large enough for containing a reserve of gasoline sufficient for remedying momentary failure of the pump in feeding the gasoline. The gasoline in excess flows away through an orifice *l*, provided with a tube acting as overflow tube.

Conduits *n*, Fig. 4, open in this chamber, above the level of the liquid; the number of these conduits is equal to that of the rows of choke conduits. Each of these conduits *n* opens in a small chamber *o* in which is arranged a block *p* pressed upon its seat by a spring *p*¹. This block is provided with openings, allowing the gasoline to enter therein, and with a calibrated hole *q* controlling the outflow of gasoline. The gasoline issuing from the orifice *q* enters a longitudinal chamber *r*, from which it passes into each of the choke tubes of the row, through holes *s*.

Owing to this arrangement, the supply of gasoline is ensured. Each row of choke conduits is separately fed by a single calibrated hole. The gasoline is atomized in the conduits *r*, which constitute preliminary vaporizing chambers. It is to be noted that this atomization is effected in the said conduits *r* being thus sheltered from the action of air, thereby avoiding the well known inconveniences of frosting.

The gasoline mist formed in each of the conduits *r*, is sucked through the row of choke conduits which are uncovered, at the moment under consideration, by the movable screen *e*. The vaporized mixture formed by addition of elementary mixtures is collected in the funnel constituted by the conduit *h*, and directly enters the engine. The new carburetor can have any number of rows of choke conduits; this number can be reduced to one, or two, three, five rows, etc., can be provided.

In the modification shown in Figs. 6 to 11, the block *a* has seven rows of choke conduits, two of which *c*¹, *c*², are used when running at slow speed. The screen *e*, which controls the number of rows in service at a given moment, is constituted by a very thin and nearly rigid blade moving in the narrow space between the block *a* and the carburetor body which are separated by thin wedges *i*.

Gasoline is admitted at *l*, in a quantity much greater than that consumed by the carburetor and the excess constantly flows away at *l*¹, so that a continuous circulation of gasoline is obtained, and it is in the stream thus formed that the carburetor sucks the quantity of fuel necessary at every instant. The gasoline enters a tank *m* arranged on the down side of the carburetor; from this tank, it passes through a conduit *t* arranged parallel to the row of vertical wells *n* feeding the

rows of choke conduits. The gasoline passes over a weir u , and the excess flows away through a conduit l^1 .

When the engine operates, the gasoline rises in the vertical wells n , at the base of which is arranged a filter x constituted for instance by wire gauze. The gasoline, reaching the level $N-N$ is above the spraying nozzles v . Each spraying nozzle is constituted by a very thin blade, of a few hundredths of a millimeter, in which is perforated one or more similar orifices v^1 , Fig. 11, of very small cross section, so that upon stoppage, the gasoline does not flow but that a very small partial vacuum is sufficient for spraying it.

Gasoline having passed through the spraying nozzles is atomized and enters the chambers r in the form of a mist. From these chambers, it passes into the choke conduits. It will be noted that each chamber is connected by small channels s to the choke conduits which are placed at its right and left-hand sides. It results therefrom that when the screen uncovers for instance the three first rows of choke conduits, the inlet cones of the choke conduits of the fourth row enter in action as shown at s^1 , Fig. 6, so that, when the screen e is urged in the direction for uncovering the fourth row, the action of this fourth row has already begun. This ensures a perfect continuity in the operation of all the rows of choke conduits, thus avoiding any interruption in the operation of the carburetor. This double feeding of the choke conduits ensures a perfect connection between the same.

In the arrangement which has just been described, a very accurate control of the carburation can be obtained by increasing the number of choke conduits.

The feeding of the choke conduits on both sides has not only for effect to ensure better operation of each of them, but also to combine the operation of two adjacent rows, this being important when putting these rows in or out of action. Dead zones and interruptions in the carburation are thus avoided, whatever may be the position of the screen e .

The constitution of the spraying nozzle by an extremely thin blade prevents it from becoming obstructed as no impurity can be retained with such a small thickness. Moreover, this arrangement allows to punch the holes and to obtain rig-

orously calibrated holes, this avoiding the control of the latter.

By raising the gasoline above the spraying nozzles, the atomization of the gasoline is easily ensured, even when the engine runs at the smallest speeds, and starting easily takes place even in cold weather, without necessitating any supplementary contrivance.

The constitution of the screen e by a thin rigid blade allows of giving it an exact thickness and of reducing to a few hundredths of a millimeter the interval between the block of choke conduits and the carburetor body, interval in which the screen moves.

The above arrangements are of course given by way of example only; the constructional details, forms, dimensions and materials used can be varied according to circumstances without departing thereby from the scope of the invention.

What I claim as my invention and desire to secure by Letters Patent is:

1. In a carburetor a plurality of air inlets arranged in rows communicating with the atmosphere and adapted for communication with the fuel inlet of an explosive engine, a fuel nozzle common to the air passages of each row, each nozzle having an orifice, means for successively closing communication between the respective rows of passages and the intake of the engine and means for supplying liquid fuel to the orifice at a pressure insufficient to cause discharge of the liquid fuel therethrough when the external pressure is at atmospheric.

2. In a carburetor as claimed in claim 1 wherein the means for supplying the liquid fuel comprises a reservoir for the liquid fuel provided with an overflow for determining the level of the liquid fuel, and chambers above the fuel nozzles and in communication with the reservoir so that the level of the liquid fuel determined by the overflow is above the fuel nozzles.

3. A carburetor as claimed in claim 1 wherein the fuel nozzles are constituted by thin plates.

4. A carburetor as claimed in claim 1 wherein the fuel nozzles are constituted by thin plates provided with small holes of similar cross section.

5. A carburetor as claimed in claim 1 wherein the air inlets are supplied with fuel from two opposite sides.

AUGUSTE CHANARD. 50.
